[57] ABSTRACT

A cart is provided for use with a kidney dialysis machine. The cart incorporates both a tank for the saline solution and a sliding tray for supporting the pump, filter and other associated equipment and controls therefor. The sliding tray top is mounted for limited sliding movement and in one position is centered on the top of the cart and in an operating position is shifted to one side to expose an opening in the top of the tank mounted below the tray. All operating units and controls are incorporated in the cart along with the tank.

CART FOR DIALYSIS MACHINE

BACKGROUND OF THE INVENTION

1. Field of the Invention

This invention relates generally to mobile medical equipment and more particularly is directed towards a new and improved cart for use with kidney dialysis machines.

2. Description of the Prior Art

Artificial kidney machines or dialyzers have reached the stage of development where they are now in common use in the hospital and, to some extent, in the home. The function of the kidney dialysis machine is to duplicate, at least in part, the functions of a healthy kidney where, because of disease or injury, the natural kidney is unable to carry out its function which is one primarily of filtering. Normal kidneys not only perform excretion functions but also regulate the salt and water content of the body. If the kidneys fail to function properly other parts of the body are adversely affected and can result in death if not remedied. The artificial kidney provides rapid correction of blood chemistry and allows the kidneys to rest or to supplant to a substantial extent the function of the natural kidney.

The apparatus involved in an artificial kidney is rather elaborate including a dializer which contains a membrane and rinsing liquid by which the blood is filtered and oxygenated, a pumping system, a heating system and controls and oxygen supply system. Heretofore, the apparatus has been assembled on a number of different tables, carts, portable tanks and the like with the various components being separately transferred and then interconnected at the location where the system is to be used. This arrangement has been quite unsatisfactory since it occupies a large amount of floor space and has involved a number of separate mobile parts which must be connected and disconnected after each use and movement.

Accordingly, it is an object of the present invention to provide a new and improved cart integrating all of the components into a single mobile unit occupying a small amount of space and one that is easily portable from room to room. Another object of this invention is to provide a compact, integrated cart for a dialysis machine that is easy and convenient to use and quickly cleaned after each use.

SUMMARY OF THE INVENTION

This invention features a compact cart for a dialysis machine comprising a frame, preferably of rectilinear construction, rollers mounted to the base of the frame for allowing free movement of the cart over a floor, a tank mounted within the frame adapted to contain a dialyzing medium such as a saline solution for use with the dialysis machine and a horizontally flat sliding tray mounted to the top of the frame for supporting the pump, filter and other components. A control box is mounted to the end of the frame with the control dials, etc., on the top thereof. The sliding tray is provided with rollers and rides on a set of rails attached to the frame with stops provided for limiting the movement of the tray in either direction. The tray is movable to an extent sufficient to expose the opening formed at the top of the tank when the unit is in use and to close over the top of the tank when the unit is not in use.

BRIEF DESCRIPTION OF THE DRAWINGS

FIG. 1 is a view in perspective of a cart for a dialysis machine made according to the invention,

5 FIG. 2 is a view similar to FIG. 1 but showing the tray in an open position,

FIG. 3 is a detail view in side elevation thereof, and,

FIG. 4 is a detail sectional view showing the slide mechanism for the tray.

10 DETAILED DESCRIPTION OF THE PREFERRED EMBODIMENT

Referring now to the drawings the reference character 10 generally indicates a rectilinear framed cart 15 formed by vertical frame members 12, one at each corner thereof, connected to top and bottom frame members 14 and 16, respectively, extending about the sides, front and rear of the frame to form a rigid framed structure. The frame members may be of any suitable structural material such as stainless steel, aluminum, wood or the like and provide a framework for a relatively large rectilinear tank 18 mounted within the frame. The tank 18 preferably is fabricated of a relatively rigid plastic material and dimensioned to fit snugly within the framework. The tank includes a top wall 20 substantially co-planar with the top frame members 14 and formed with a rectilinear offset opening 22 providing access to the tank through a removable or hinged cover 23. The tank 18 is also provided with a drain valve 24 at the base thereof allowing the tank to be emptied when desired. The frame is provided with four casters 26, one at each corner thereof, to allow free mobility of the cart in any direction permitting the cart and its equipment to be moved from room to room quickly and easily.

35 On the left-hand end of the cart 12 as viewed in FIG. 1 there is mounted a housing 28 for electronic controls and circuits used in the operation of the dialysis machine. Knobs, dials, switches, etc., are mounted conveniently on the upper end of the housing 28.

40 Mounted to the top of the cart is a sliding tray 30 adapted to support components of the dialysis machine such as a pump generally indicated by reference character 32 and a dialysis coil generally indicated by reference character 34. Other accessory components may 45 also be placed on the tray 30.

The tray 30 is generally rectangular in outline corresponding with the dimensions of the top of the frame but with a slight overhang along the sides. Preferably, 50 the tray is fabricated of a plywood or pressed wood core 36 the outer surfaces of which are laminated with a plastic stratum 38 such as Formica or the like to provide a strong, rigid support for the dialysis components and a surface that is easily cleaned.

55 Extending downwardly from opposite sides of the horizontal portion of the tray are two elongated side panels 40 and 42 attached to the underside of the core 36 by cementing, fastening, or other means. The panels depend perpendicularly from the underface of the tray and extend substantially the full length thereof. Each of the panels is provided with a pair of spaced rollers 42 and 44 which may be of metal or a plastic such as nylon and are supported each by a shaft 46 extending through the panel with the wheel mounted on the inside end thereof. A spacer 48 is provided between the inner face of the panel and the wheel and the wheel is retained on the shaft 46 by a cotter pin 50 passed through a hole

formed in the end of the shaft. The wheels ride on the upper frame members 14 which serve as rails and which preferably are of a hollow square cross-section and of stainless steel material to provide strength and durability. In order to limit transverse motion of the tray, a rib 52 may be fastened to the inner face of the panels 40 and 42 oppositely the rails 14 providing a slight clearance therewith. Preferably the rib is of a plastic material such as nylon which will allow free longitudinal motion of the tray and will slide freely with respect to the rail if in contact with it. In place of the rib 52 several plastic headed pins may be attached in a line to the inner face of the panel to laterally position the tray. The rollers 42 and 44 are mounted to the side panels towards one end thereof with the rollers 42 located almost to the left-hand end while the rollers 44 are mounted towards the middle of the panels. In this fashion the rollers will remain in contact with the rails even though the tray has been shifted to the right as shown in dotted line in the drawings.

In order to limit the longitudinal motion of the tray, stops 54 and 56 are provided on each of the panels 40 and 42. The stops typically are in the form of L-shaped legs attached to the lower edges of the panels and project inwardly under the rails 14 so as to butt against the upright frame members 12 in either extreme position of the tray. The stops are mounted to allow limited longitudinal movement of the tray with the stop 54 located near the extreme left-hand edge of the panel while the stop 56 is located more towards the center of the panel to the right of the roller 44 as viewed in FIG. 3. In this position the rollers will be kept on the rails in either position of the tray and the left-hand motion of the tray is limited to the closed position as shown in full line in FIG. 2 while its right-hand motion will be limited by the stop 56 which is sufficient for the tray to expose the tank opening 22. Typically, this motion would be on the order of 7" or so. The stops 54 and 56 not only serve to limit the longitudinal motion of the tray but also prevent the tray from being tipped should the tray become unbalanced when open by reason of the weight and position of the units 32 and 34. Since the stops extend in under the rails such tipping of the tray is prevented.

The cart provides a compact and convenient dialysis station integrated within one mobile unit. All of the dialysis equipment, including the tank are on the cart in a very compact unit which is easily rolled about from room to room. When the dialysis machine is to be operated, the attendant merely rolls the tray back and thus has direct access to the tank opening. Once the treat-

ment has been completed, the tray is returned to its normal compact position and the cart may be moved to another location. The tank is readily drained and cleaned and all components are conveniently accessible.

Having thus described the invention what we claim and desire to obtain by Letters Patent of the United States is:

1. A cart for use in a mobile kidney dialysis station,

10 comprising

- (a) a frame including horizontally disposed top and bottom members of rectangular outline and vertical members connecting said top and bottom members,
- (b) a waterproof tank generally corresponding in size and shape to said frame mounted within said frame,
- (c) said tank being formed with an opening at the top thereof adjacent one end thereof,
- (d) roller means mounted to the bottom of said frame and supporting said cart for free rolling movement, and
- (e) a flat horizontally disposed tray substantially co-extensive with said top frame member and mounted to said top member for limited sliding movement relative thereto,
- (f) said tray being adapted to support kidney dialysis equipment and in one position said tray covering said tank opening and in another position said tray exposing said tank opening,
- (g) said top frame member including a pair of parallel rails, one fixed horizontally along each side of said top member and said tray includes a plurality of wheels mounted to said tray and engaging said rails,
- (h) said tray including a pair of parallel depending panels extending longitudinally along each side thereof and supporting said wheels, and,
- (i) a plurality of inwardly extending stop members mounted to said panel projecting under said rails and engageable with said vertical frame members at either extreme position of said tray, said stop members being spaced apart to limit the travel of said tray from a closed position fully over said top frame member to an open position exposing said tank opening.

2. A cart according to claim 1 wherein said roller means are casters.

3. A cart according to claim 1 including at least one low frictional boss mounted to the inner face of each panel in opposing spaced relation to said rails.
